UNITED STATES PATENT OFFICE

MARCUS B. BEHRMAN, OF BROOKLYN, NEW YORK, ASSIGNOR, BY MESNE ASSIGNMENTS, TO THE AMERICAN SAFETY RAZOR CORPORATION, OF BROOKLYN, NEW YORK, A CORPORATION OF VIRGINIA

RAZOR

Application filed June 19, 1926. Serial No. 117,035.

This invention relates to safety razors of the type which has a single combination of elements adapted not only for shaving but for stropping of the blade used thereby and 5 is an improvement upon my Patent No. 1,432,949, granted on Oct. 24, 1922.

The invention has for an object thereof the provision of a safety razor of simple construction adapted to use standard types of 10 blades and which may alternatively be used for shaving or, without the addition of any parts, adapt itself for use with the strop to sharpen the blade used thereby.

In the more preferred embodiment, my invention 15 contemplates as an object thereof the provision of a safety razor adapted to use a double edged flexible blade in which a blade holding assembly is provided cooperating with a frame guard and hand holding portion to hold and flex a blade for shaving purposes with varying degrees of shaving positions and which may, by simple adjustment, be converted into a stropping device 20 for the blade without complete dismounting of the razor and its attached blade holding assembly.

The invention still further has for an object thereof the provision of a safety razor adapted to be used as a stropping device 25 which includes a blade holding assembly adapted to cooperate with a frame and guard for flexing a blade arcuately to obtain varying degrees of shaving positions, which may alternatively be adjusted to receive a strop 30 whereby the blade assembly is so mounted relatively to the frame portion as to automatically position the blade for best stropping effects in its movement upon a strop.

The invention still further has for an object 35 thereof the provision of a safety razor including a blade holding assembly normally adjustable for shaving as desired, including means of ready replacement of the blade and which may, by simple adjustment, permit the blade to be stropped in situ without dismounting or disconnecting any parts thereof or the blade assembly.

In its preferred embodiment, my invention 40 has for an object thereof the provision of a safety razor suitable as a stropping device

for blades including a frame guard and handle portion adapted to cooperate with a blade holding assembly arranged to be mounted relatively to said frame and handle so that a strop may be inserted between said blade 55 assembly and frame and by movement along the length of the strop, particularly where a double edged blade is used, automatically obtain position of the blade relative to the strop for best stropping effects. In the embodiment wherein a flexible double edged blade is used, the blade assembly serves as a blade curving and flexing device by being tensioned or bent over and upon the frame and guard members provided. The blade assembly is so constructed as to of itself permit replacement of the blade thereon and without the addition or removal of any parts but merely by disengagement of the blade assembly operating member is capable of being 60 converted into a blade stropping device. 65

The invention still further has for an object thereof the provision of a stropping safety razor in which a blade holding assembly is arranged to serve the double purpose of a 70 stropping device having particular utility with a double edged flexible blade so as to automatically position the assembly for stropping alternately each of the cutting edges provided and which assembly may be 75 readily adjusted relative to a frame, including a guard, for flexing the blade into positions best suited for shaving.

The invention still further contemplates, as an object thereof, the provision of a safety 80 razor which includes means for affording ready access to a blade holding assembly for replacement of a shaving blade to the assembly, simultaneously serving as means to stroop a blade in situ and curve the blade for 85 shaving purposes against an arcuately curved frame member, the means to arcuately curve the blade simultaneously serving to augment the locking action of the blade holding assembly to prevent accidental unlocking of 90 the blade relative to the blade holding assembly.

My invention still further contemplates as 95 an object thereof the provision of a safety razor having a blade holding assembly pivot- 100

ally and slidably mounted relatively to a frame, including a guard, so that a strop may be inserted between the assembly and the frame to provide best positions for stropping of the cutting edges of the blade and where a double edged blade is used, automatically position alternately each of the cutting edges in contact with the strop by moving along the length of the stropping member, the parts being so formed that without any additional members, the assembly serves the functions of a blade seating and a blade shaping member when used in association with the frame including the guard member.

In general, my invention contemplates as an object thereof the provision of a safety razor which is adapted to be used with a double edged flexible razor blade which may be used for shaving purposes or for stropping in situ without substantially disconnecting any of the parts but simply by a tensioning operation of the associated members thereof.

For the attainment of these objects and such further objects as may appear herein or be hereinafter pointed out, I make reference to the accompanying drawing forming a part hereof, in which

Figure 1 is a perspective view of my assembled safety razor;

Figure 2 is a partial section taken on a line 2—2 of Figure 1;

Figure 3 is a view similar to Figure 2 with parts adjusted out of the shaving position and ready for stropping;

Figure 4 is a section on a line 4—4 of Figure 2;

Figure 5 is a section on a line 5—5 of Figure 3 with my device shown in connection with a strop;

Figure 6 is an end elevation of the view shown in Figure 2 from the right end thereof;

Figure 7 is a plan view of my device with the blade shaping member removed.

Referring to the drawings, my device has been illustrated as best adapted for use in connection with a double edged thin flexible blade and comprises a frame member 10, preferably arcuately contoured, having its oppositely disposed side edges formed as guards or combs 11 and 12. An annular member 13, preferably hollow, is fixedly attached to the frame at its lower central portion by screw engagement upsetting or in any other desired manner and through the central portion thereof there is arranged a tensioning member 14 disposed therethrough, having at its outer end a knurled knob 15 and at its upper end a screw engaging portion 16, for purposes which will be hereinafter described.

Mounted upon the frame 10 previously described, I provide a blade holding assembly comprising a blade retaining member 17 and a blade shaping member 18 separably con-

nected as by a hinged joint formed of lugs 19 and a pin 19' passing therethrough. There is provided on the blade retaining member downwardly disposed extension members 20 and 21 having at their extremities pivot pins 22 and 23. The extension members 20 and 21 and the pins carried thereby are arranged to pass into the respective slots 25 in the frame member 10, the side walls of the latter being formed with guide slots 26, 27 to permit relatively sliding movement of the pins 22 and 23 therein. The upper end walls 28 of the guide slots 26, 27 are preferably suitably formed to permit pivotal movement of the pins when abutting thereagainst.

As previously described, the blade holding assembly is composed of blade retaining member 17 and blade shaper member 18, and the member 17 is formed with blade positioning lugs 29 adapted to hold a thin flexible double edged blade 30 and where I provide an arcuate blade shaping member, the retaining member 17 is suitably spaced and the blade positioning lugs 29 are of suitable length to hold the blade centered throughout relative movement of the blade between the parts 17 and 18, due to flexing and extension of the blade in a manner which will be hereinafter described.

For permitting ready access and replacement of the blade 30 between the separable parts 17 and 18, suitable means are provided and where I have connected the members 17 and 18 by a hinged joint 19 and 19', the oppositely disposed edge of the member 18 is provided with a latch member 31, hinged at 32 by the lugs and pin 33 and 34, respectively. This latch is provided with a slot of contour approximating the figure 8 and herein numbered 35. The latch 31 is made of a length sufficient to engage the pin 23, the latter member being formed upon its side walls with an annular groove 36 adapted to engage the slot 35 and be locked therewith, due to the resilience of the side walls of the slotted latch 31 previously described.

As will be observed, the blade assembly may have relative sliding movement limited by the engagement of the pins 22 and 23 with the abutting walls 28 and when moved to the limited position, as shown in Figure 3, may also have relative pivotal movement to the frame and handle member 10 and 13. In this position also, the latch member 31 may be released from the pin 23, as shown in dotted lines in Figure 2, and more clearly shown in Figure 7, to permit the replacement of the blade member 30 between the blade assembly members 17 and 18.

Where I use a double edged thin flexible blade, it is preferred to urge the blade against the frame member 10 to arcuately shape the same in accordance with best shaving angles and for this purpose means are provided to urge the blade assembly against the arcuate-

ly shaped frame. There is therefore provided on the blade retaining portion 17 a screw threaded portion 37 adapted to engage the screw threaded member 16. Engagement of the portions 16 and 37 by turning of the knurled knob 15 will serve to urge the blade holding assembly upon the frame. The space provided between the members of the assembly 17 and 18 will permit the shaper portion 18 to accomplish its intended function of shaping the blade 30 in a well known manner. The effect produced is best illustrated in Figures 4 and 6, showing the limiting position of the blade assembly upon the frame curving the blade to its fullest extent. In this position also, the locking of the blade assembly is augmented, due to tension applied to the member 17, the blade shaper member 18 abutting against the frame 10 tending to exert tension upon the hinge 19 and the latch and pin connection 23 and 31.

Upon release of the screw connecting member 16, various angular displacements of the blade may be obtained and upon full release, as shown in Figures 3 and 5, the blade will assume the fullest extension, permitting unhinging of the parts 17 and 18 for the replacement of the blade member 30 therebetween. In the position shown in Figure 3 where the blade assembly is latched and relatively located to be fully extended, a strop member 38 may be positioned therebetween as shown in Figure 5. In this position longitudinal movement along the length of the strop 38 will alternately present the edges of the blade 30 in stropping relation, either by tilting of the handle 13 or, where I have arranged the blade assembly for pivotal movement relative to the frame, the tilting action necessary for proper angular positioning of the blade is automatically accomplished as the device is moved back and forth along the length of the strop 38, due to frictional engagement of the assembly with the strop member.

It will thus be observed that I have provided a safety razor suitable for use in its well known manner and which is adapted for stropping a blade in situ, without disconnecting or dismounting any of the portions thereof, but simply by releasing the screw connection similar to that used in adjusting the angle of the flexible blade for shaving purposes. Thus, also, no parts of my device are separated from the assembly to change the razor to a stropping device but in a simple manner and by using the simplest number of parts for providing a shaving device, I also provide a stropping device without any additional parts or unusual arrangement of the members relatively to each other. The assembly for holding the blade is further made proof against accidental separation of the blade from the separable blade assembly by augmenting the locking engagement against the latch 31 and the pin 23 when tension is

applied to the member 17 of the blade assembly.

It will be further observed that for certain purposes the handle portion 13 may be a single structure by permitting the shoulder 13' of the handle 13 to have rotating action within the frame 10 and to make the member 14 integral therewith. In this manner a single member may serve as a handle portion and a blade assembly tensioning device.

Having thus described my invention and illustrated its use, what I claim as new and desire to secure by Letters Patent, is:

1. In a safety razor, a frame having opposite guards, a blade holder comprising two superposeable portions adapted to sandwich a double-edged blade therebetween, means including pivot pins for associating the holder with the frame to permit adjustment thereof toward and away from the frame and also pivotal movement thereof with respect to the frame when spaced therefrom, and means for locking said portions together, said last named means comprising a tab engaging one of said pivot pins.

2. In a safety razor, a frame having opposite guards, a blade holder comprising two superposeable portions adapted to sandwich a double-edged blade therebetween, means including pivot pins for associating the holder with the frame to permit adjustment thereof toward and away from the frame and also pivotal movement thereof with respect to the frame when spaced therefrom, means for locking said portions together and comprising a tab engaging one of said pivot pins, and means for securing the holder against the frame to force the blade edges against said guards, said last named means separably engaging one of said portions.

3. In a safety razor, a frame having opposite guards, a blade holder comprising two superposeable portions adapted to sandwich a double-edged blade therebetween, one of said portions having a threaded part, means for associating the holder with the frame to permit adjustment thereof toward and away from the frame and also pivotal movement thereof with respect to the frame when spaced therefrom, and means for securing the holder against the frame to force the blade edges against said guards, said means comprising a threaded handle member adapted to separably engage said threaded part of said holder portion.

4. In a safety razor, a frame having opposite guards, a blade holder composed of two superposed portions adapted to sandwich a double-edged blade between the portions thereof, the upper or cap portion being spaced from the lower portion and having a concave under-surface, means articulating said holder to the frame to permit spacing thereof from the frame for stropping purposes, and means engaging one of said holder

portions for drawing the holder against the frame and thereby flexing the blade against said concave under-surface for shaving purposes.

5. In a safety razor, a frame having opposite guards, a blade holder composed of two superposed portions adapted to sandwich a double-edged blade between the portions thereof, the upper or cap portion being spaced from the lower portion and having a concave under-surface, means articulating said holder to the frame to permit spacing thereof from the frame for stropping purposes, and means removably engaging the lower holder portion for drawing the holder against the frame and thereby flexing the blade against said concave under-surface for shaving purposes.

6. In a safety razor, a frame, a blade seat mounted thereon and having opposite guards, a blade holder composed of two spaced superposed portions adapted to sandwich a double-edged blade between them, the upper or cap portion having a concave under-surface and being of such a width that its lateral edges lie substantially over said opposite guards, means articulating said holder to the frame to permit spacing thereof from the frame, whereby the blade is retained in substantially flat condition for stropping purposes, and means engaging one of said holder portions for drawing the holder against the frame and thereby clamping the blade adjacent to the cutting edges thereof onto said guards and beneath the lateral edges of said cap portion.

7. In a safety razor, a frame, a blade seat mounted thereon and having opposite guards, a blade holder composed of two spaced superposed portions adapted to sandwich a double-edged blade between them, the upper or cap portion having a concave under-surface and being of such a width that its lateral edges lie substantially over said opposite guards, means articulating said holder to the frame to permit spacing thereof from the frame, whereby the blade is retained in substantially flat condition for stropping purposes, and means removably engaging the lower holder portion for drawing the holder downwardly toward the blade seat and thereby flexing the blade against said concave under-surface for shaving purposes, the lateral edges of the cap portion bearing downwardly upon the blade adjacent to the cutting edges thereof.

8. In a safety razor, a frame provided with an upwardly convex blade seat having opposite guards, a blade holder composed of two superposed portions adapted to sandwich a blade between them, means articulating the holder to the frame to permit adjustment thereof toward and away from the frame and also pivotal movement thereof with respect to the frame when spaced there-

from, and means adapted to engage the lower blade holder portion to draw the holder and the sandwiched blade toward the frame and secure it thereto, the cap or top portion of the blade holder having a concave under-surface adapted to bear downwardly upon the blade seat and thereby clamp the blade in flexed condition upon said seat.

9. In a safety razor, a frame provided with a blade seat having a medial depression, a blade holder, means for associating the holder with the frame to permit adjustment thereof toward and away from the frame and also pivotal movement thereof with respect to the frame when spaced therefrom, said holder comprising two superposed portions adapted to sandwich a double-edged blade therebetween, the lower portion being adapted to fit into said depression and the cap portion being adapted to bear against the blade seat on opposite sides of the depression, when the holder is moved toward the frame.

In testimony whereof, I have hereunto signed my name.

MARCUS B. BEHRMAN.
